UNITED STATES PATENT OFFICE.

FRANK MAGGIO, OF PHILADELPHIA, PENNSYLVANIA.

DESIGN FOR A RADIOCABINET.

Application filed June 7, 1927. Serial No. 22,361. Term of patent 7 years.

To all whom it may concern:

Be it known that I, FRANK MAGGIO, a citizen of the United States, residing at the city of Philadelphia, in the county of Philadelphia and State of Pennsylvania, have invented a certain, new, original, and ornamental Design for a Radiocabinet, of which the following is a specification, reference being had to the accompanying drawing, forming part hereof, and in which—

Fig. 1, is a view in perspective of a radio cabinet and embodying my new design.

Fig. 2, is a view in plan of a radio cabinet embodying my new design.

Fig. 3, is a view in end elevation of a cabinet embodying my new design.

I claim:

The ornamental design for a radiocabinet, as shown.

FRANK MAGGIO.
